UNITED STATES PATENT OFFICE.

JOHN H. ENGLAND AND EDWARD HORTH, OF CHICAGO, ILLINOIS.

AUTOMATIC RAIL-PUNCHING MACHINE.

SPECIFICATION forming part of Letters Patent No. 269,650, dated December 26, 1882.

Application filed July 5, 1882. (No model.)

To all whom it may concern:

Be it known that we, JOHN H. ENGLAND and EDWARD HORTH, of Chicago, in the county of Cook and State of Illinois, have invented 5 certain new and useful Improvements in Automatic Rail-Punching Machines; and we do hereby declare that the following is a full, clear, and exact description thereof, reference being had to the accompanying drawings, and 10 to the letters of reference marked thereon, which form a part of this specification.

The object of our invention is to produce a machine that will punch the holes for the fish-bar-connection bolts into a steel rail simultaneously with sawing off the ends of such rail while it is hot; and it consists of a punching-machine that is attached to each end of a rail-sawing machine, and that is operated by the shifting of the rail-carriage toward the saw, 20 all as hereinafter described and specifically claimed.

In the accompanying drawings, Figure 1 represents an end elevation of a rail-sawing machine having our punching-machine attached; 25 Fig. 2, a front elevation of one end of the same; Fig. 3, a vertical cross-section of the punching-machine detached; Fig. 4, a sectional front elevation, and Fig. 5 a sectional plan view, of the same.

Corresponding letters in the several figures 30 of the drawings designate like parts.

A denotes the bed or foundation-plate of the rail-sawing machine, that is provided on top with parallel longitudinal guide-strips, upon 35 which the inclined pedestal-bearings B and B'—two upon each end of such bed—are bolted in a manner to be longitudinally adjustable thereon. Each pair of pedestal-bearings B and B' carries an arbor, C, upon the exteriorly-over-hanging end of which is secured, in the usual manner, a circular saw, D, and upon the middle portion, between its bearings, is mounted 40 upon such arbor a pulley, E, for rotating the saw by a belt.

Against the front face of each pedestal-bearing B and B' is bolted a bracket, F, the rear base of which rests also upon the bed-plate A, and is bolted thereto. These brackets F have strips to their top faces for horizontally and 45 laterally guiding the carriage G, and the carriages G, to both ends of the machine, are con-

nected by a bar, H. A die, I, is secured upon the exterior end of each carriage G next to the saw. Such die I is of a width to fit between the head and the bottom flange of the steel rail a, the overhanging end of which is to be cut off, which rail is placed sidewise, so that its ends rest with their web thereon, while the middle portion of the rail is supported by bar H.

Each carriage G is connected by a rod, b, with a vertical rocker-arm, c, and these rocker-arms c are connected again, each by a rod, d, with a crank, e, and both cranks e are mounted upon the extreme ends of a shaft, f, that is 55 journaled in pedestal-bearings g, and has a hand-wheel or other means for rotating it in a manner that an entire revolution of such shaft f will transmit a simultaneous reciprocating movement of both carriages G, and will move 60 the rail a toward and away from the saws D, which will cut off the ends of such rail, the pedestal-bearings B being placed the proper distance for cutting the rail the required length.

So far as described is the usual construction of a rail-sawing machine, which we do not claim as our invention, our improvements consisting of the rail-punching machine attached thereto, and which we will now proceed to describe.

Each carriage G we provide with a vertical plate, J, having a journal-box, h, to its top, and being stiffened by a brace, i. The front face and side and rear edges of plate J are 85 planed to form the guides for a slide-block, K, that has side and rear flanges lapping over the edges of plate J, so as to insure a steady vertical movement thereon. This slide-block K has two pair of eye-lugs, j, to its top, between 90 which are pivotally secured by a bolt the lower ends of two bars, L. Two bars, M, of about equal lengths with bars L, are connected by a pin at their lower ends, that is pivoted in journal-box h of plate J, and the upper ends of 95 bars L and M are pivotally connected by a bolt, l, between the bifurcated ends of two rods, N, the opposite ends of which rods N are again pivoted to eyebolts K, that are secured to a standard-bracket O, which is rigidly bolted to the pedestal-box B. As will be noticed, the bars L and M being thus pivot-

ally connected on top by a bolt, *l*, that is laterally held stationary by the rods *N*, while their bottom fulerums are placed laterally apart, the shifting of the carriage *G* toward the saw will cause the pushing downward of the slide-block *K*, and the shifting of the carriage *G* away from the saw will cause the raising of the slide-block *K*, the connections of the bars *L* and *M* being such that they will operate in the manner of a toggle-joint, and can exert a great force by their movement. The distance of reciprocation of carriage *G* is indicated by dotted line *x*, and the distance of vertical movement of slide-block *K*, that is caused by the motion of the carriage, is indicated by dotted line *y*. The lower portion of slide-block *K* is chambered out to provide two compartments between the side flanges and an intermediate flange, *m*, which compartments are closed in front by a plate, *n*, secured against the slide-block by screws. Into these compartments are inserted two blocks, *o* and *p*, which, with their top ends, butt against the solid upper portion of slide-block *K*, and in their lower ends these blocks *o* and *p* have conical sockets for inserting the punches *q* and *r*, which are secured therein, each by a setscrew. The punch-blocks *o* and *p* are suspended and rigidly held in their respective receptacles each by two longitudinal screw-rods, *s*, and by two transverse screws, *t*, that are passed through screw-threaded holes in the punch-blocks. The screw-rods *s* are pivoted with their ends in grooves between the side and center walls of their respective receptacles, and are reached for adjustment by a wrench passed through vertical slots in plate *n*. The screws *t* are pivoted with their points in grooves of the rear wall of the receptacles, with their squared heads projected through longitudinal slots in plate *n*, and so as to form a shoulder against such plate *n*. Sufficient space is allowed in these receptacles longitudinally and laterally for adjusting these blocks *o* and *p* in either direction by turning the screws *s* or *t*.

The die *I*, upon which the rail is placed, is perforated with two downwardly-flaring holes that will form the females for the punches *q* and *r*, and the carriage *G* is slotted below such die-holes for the punched-out pieces to drop through. The die *I* being placed on the carriage *G* at proper distance relative to the saw *D*, and the punches *q* and *r* being adjusted to be vertically in line with the holes in die *I*, every rail, while being cut proper length, will be punched at proper distances from its ends, so that after once adjusted all rails will come out uniform.

Steel rails, while cold, cannot be punched, but have to be drilled, which is expensive, while with our device no extra labor is ex-

pended with providing the bolt-holes for completing a rail.

A punching-machine may be constructed in many ways, and there may be different devices for connecting such a punch with the carriage and frame of a rail-sawing machine to perform the punching simultaneous with cutting the rail the proper length, and therefore we do not wish to be restricted to the particular construction herein described and shown.

Our device can be made to work just the same in connection with a rail-sawing machine in which the rail to be cut is placed stationary and the saws are reciprocated.

The above-described punching attachment to rail-sawing machines, as will be readily seen, is simple and reliable for the work to be performed, and cannot well get out of order, while at the same time it is time, labor, and room saving for the manufacturer.

What we claim is—

1. The combination, with a rail-sawing machine, of a punching-machine consisting of standard-frame *J*, that is rigid with the rail-carriage, sliding block *K*, that carries the punches *q* and *r*, and of suitable means for moving such block *K* vertically simultaneously with shifting the rail-carriage horizontally toward the saw for the purpose of punching the fish-bar-bolt holes simultaneously with cutting the rail to proper length, substantially in the manner set forth.

2. A punching-machine consisting of standard-frame *J*, that forms part of the rail-carriage *G*, and has pivotally-connected bars *M*, and the slide-block *K*, carrying punches *q* and *r*, and having pivotally-connected bars *L*, and both bars *L* and *M* being connected on top by a bolt, *l*, which again is connected by rods *N* with a fixed standard, in a manner that the reciprocation of the carriage will operate the punches, all substantially as and for the purpose set forth.

3. The combination, in a rail-sawing machine having pedestal-bearings *B*, that carry arbors *C* and saws *D*, and a carriage, *G*, that supports dies *I*, of the punching-machines, each consisting of a standard-frame, *J*, and slide-block *K*, that holds the punches *q* and *r*, and is operated by bars *L* and *M* and rods *N*, connected, substantially as described, to operate in the manner set forth.

In testimony that we claim the foregoing as our invention we affix our signatures in presence of two witnesses.

JOHN H. ENGLAND.
EDWARD HORTH.
